UNITED STATES PATENT OFFICE.

NICHOLAS LAULETTA, OF PHILADELPHIA, PENNSYLVANIA.

TABLE OR COUNTER ATTACHMENT.

1,113,793.

Specification of Letters Patent. Patented Oct. 13, 1914.

Application filed April 22, 1913. Serial No. 762,857.

To all whom it may concern:

Be it known that I, NICHOLAS LAULETTA, a citizen of the United States, residing at Philadelphia, in the county of Philadelphia and State of Pennsylvania, have invented 5 new and useful Improvements in Table or Counter Attachments, of which the following is a specification.

This invention has relation to attachments 10 especially adapted to be applied to tables or counters and it consists in the novel features hereinafter described and claimed.

An object of the invention is to provide an 15 attachment of simple construction which may be easily and readily applied to a table or counter, such for instance as is used in eating houses or places; the attachment having means for adjustably holding a napkin toward or against the breast of a diner. 20 The attachment is further provided with other means for holding various articles as for instance a cigar, a hat, newspaper, bundles and furthermore the attachment is provided with a mirror hingedly connected 25 thereto.

In the accompanying drawing—Figure 1 is a perspective view of the attachment. Fig. 2 is an edge elevation of the lower portion of the same. Fig. 3 is a sectional view of 30 the lower portion of the same.

The attachment comprises a metallic plate 1 having screw openings 2 through which screws may be passed whereby the plate may be attached to the frame of a counter or 35 table. The plate 1 is provided at one side edge with an outwardly standing lug 3 to which is pivotally attached a shank 4 carrying a sleeve 5. A rod 6 is slidably mounted in the sleeve 5 and is provided at one side 40 with notches 7. A spring member 8 is connected with the shank 5 and lies in an opening 9 provided in the side of the sleeve 5 and is adapted to line in one of the notches 7 whereby the rod 6 may be held in an adjusted 45 position with relation to the sleeve 5. The inner portion of the spring 8 passes through an opening 10 with which the shank 4 is provided and is formed at its inner end with an eye 11 which surrounds the pivot 50 between the shank 4 and the lug 3 and affords sufficient friction to hold the shank 4 at an adjusted position with relation to the lug 3.

The rod 6 is provided at its outer end with 55 oppositely disposed arms 12 which are

formed at their ends with hooks 13. A napkin (not shown) may be engaged with the hooks 13 and when a diner is sitting in front of the plate 1, the spring 8 may be disengaged from the notches 7 and the rod 6 60 may be moved longitudinally so that the napkin will be brought in close proximity to the breast of the diner. The rod 8 may then be permitted to enter the opening 9 and seat in one of the notches 7 whereby the rod 65 and the napkin will be held at the desired position with relation to the body of the user. The plate 1 is provided at its side edge with a hook 14 with which the strings of bundles may be engaged whereby the 70 bundles are held in front of the diner. The plate 1 is provided at its intermediate portion with a clip 15 which may support a newspaper. The plate 1 is provided at its upper end with a shelf 16 which may support 75 a cigar. The plate 1 is provided at its upper end with an extension 17 having a perforated lug 18 which may be secured by means of a screw or bolt to the under side of the top of the table or counter. A plate 19 80 is hingedly connected with the lower end of the plate 1 and carries a mirror 20. The plate 19 is provided at its back with a clip 21 which may receive the edge portion of the rim of a hat whereby the hat may be 85 supported.

Therefore it will be seen that an attachment of simple structure is provided which is adapted to hold various articles which are placed before a diner seated at a table or 90 counter.

Having described the invention what is claimed is:

An attachment comprising a plate having an outstanding lug, a shank pivotally connected with the lug, a sleeve carried by the shank, a rod slidably mounted in the sleeve, a spring member passing through the shank and having an eye which receives the pivotal connection between the shank and the lug 100 and frictionally engages the said pivotal connection, said spring being adapted to bear against the rod and hold the same with relation to the sleeve.

In testimony whereof I affix my signature in presence of two witnesses.

NICHOLAS LAULETTA.
